UNITED STATES PATENT OFFICE

154,840

DESIGN FOR A FILM VIEWER

Francis T. Coffey, Sr., Los Angeles, Calif.

Application April 11, 1949, Serial No. 1,908

Term of patent 14 years

(Cl. D61—1)

To all whom it may concern:

Be it known that I, Francis T. Coffey, Sr., a citizen of the United States, residing at Los Angeles, in the county of Los Angeles, State of California, have invented a new, original, and ornamental Design for a Film Viewer, of which the following is a specification, reference being had to the accompanying drawings, forming a part thereof, in which:

Fig. 1 is a perspective view of a film viewer, showing my new design, the view being taken from the rear and operating side; and,

Fig. 2 is another perspective view of the same, taken from the opposite side and showing the cover on the opposite side open, so as to disclose the inside of the viewer and the light-admitting opening at the front side.

I claim:

The ornamental design for a film viewer, substantially as shown and described.

FRANCIS T. COFFEY, SR.
